UNITED STATES PATENT OFFICE.

WILLIAM KLOTZ, OF WORDEN, ILLINOIS.

NUT-LOCK.

1,160,905.

Specification of Letters Patent.

Patented Nov. 16, 1915.

Application filed January 7, 1914. Serial No. 810,909.

To all whom it may concern:

Be it known that I, WILLIAM KLOTZ, citizen of the United States, residing at Worden, in the county of Madison and State of Illinois, have invented certain new and useful Improvements in Nut-Locks, of which the following is a specification.

My invention relates to nut locks and more particularly to a device for positively 10 locking the nut upon the bolt.

The primary object of my invention is to provide an improved locking means on the nut for preventing rotation of the same upon the bolt.

Another object of my invention is to provide a novel means for removably holding the locking member on the nut in engagement with the bolt.

A further object of my invention is to provide a device which is simple in construction, efficient in operation and one which can be manufactured and put upon the market at a minimum cost.

Other objects as well as the nature characteristic features and scope of my invention will be more readily understood from the following description taken in connection with the accompanying drawings and pointed out in the claims.

In the drawings:—Figure 1 is a top plan view of my invention showing the locking member in locked position; Fig. 2 is a top plan view of the same showing the locking member in unlocked position; Fig. 3 is a 35 transverse sectional view of my invention taken on line 3—3 of Fig. 1; Fig. 4 is a perspective view of the locking member; and, Fig. 5 is a perspective view of the keeper.

Referring more particularly to the drawings in which reference numerals designate corresponding parts throughout the different views, the numeral 1 represents the outer screw threaded end of an ordinary bolt having a plurality of longitudinally extending notches 2 arranged in uniform spaced relation on the outer surface thereof.

Screw threaded on the bolt 1 is a nut 3, provided on its upper face with a diagonally extending recess 4, the inner end 5 of which lies at right angles to the longitudinal axis of the bolt 1, thereby causing the same to lie flush with the radial faces 6 of the notches 2 and the inner side 7 of which is adapted to lie flush with the sloping faces 8 of the

notches 2 when in locked position. The bottom of the recess is provided approximately intermediate its ends with an arcuate depressed portion 9 and the sides of the recess diverge slightly from a point opposite the depressed portion 9. Pivots and loosely 55 mounted in the recess 4 by means of a pivot 10, is a locking member 11 which in this instance consists essentially of a metallic strip having an apertured ear 12 on one of its marginal edges for engagement with the 60 pin 10, and the depressed portion 9, and has its inner end 13 bent at an angle substantially obtuse to the body thereof. The extreme inner end of the locking member is beveled as at 14, and is adapted for biting 65 engagement with the radial faces of the notches.

For the purpose of removably holding the locking member in engagement with the notches 2, I have provided a keeper 15 which 70 is pivotally mounted upon the pin 10, between the outer side of the recess and the locking member, this keeper being pivoted at a point substantially adjacent the depressed portion 9. In this instance the keeper 15 75 consists essentially of a key tapering as at 16 toward its inner end, which end is provided with an opening 17 for engagement with the pin 10. In order to prevent the keeper 15 from becoming accidentally disengaged from the inner end of the recess by 80 shocks or the like, I have punched an indentation 18 on the inner longitudinal edge of the locking member.

The operation of my device is as follows: 90 The nut 3 is threaded on the bolt 1 to the desired position and until the inner end of the recess registers with one of the notches. The keeper is now moved on its pivot and pressed into wedging engagement with 95 the inner end of the locking member, which end is beveled and bites the straight face 6 of the notch 2. After the above operation, the indentation 18 is formed in the outer marginal edge of the locking member by 100 directing a blow thereagainst with a metal punch of any suitable character. To remove the nut, all that is necessary is to remove the indentation 18 in the locking member and release the same by swinging the 105 keeper to the opposite end of the recess.

It will be obvious to those skilled in the art to which this invention relates that

modifications may be made in detail without departing from the spirit or scope of the invention as defined by the appended claims.

Having thus fully described my invention 5 what I claim as new and desire to secure by Letters Patent is:

1. In combination with a bolt having a plurality of longitudinal notches, of a nut provided with a recess, a locking member 10 pivotally and loosely mounted in said recess, and cam means for releasably holding said locking member in engagement with one of said notches.

2. In combination with a bolt having a plurality of longitudinal notches, of a nut provided with a recess, a locking member pivotally mounted in said recess, the inner end of said locking member bent at a substantial obtuse angle to its body, and a keeper pivotally mounted for releasably holding the inner end of said locking member in engagement with one of said notches.

3. In combination with a bolt having a plurality of longitudinal notches, of a nut provided with a diagonally extending recess, the sides of said recess diverging slightly from a point intermediate its ends, a locking member pivotally mounted in said recess the said locking member having its inner end arranged at an angle substantially obtuse to the body thereof, and a tapering wedge member pivotally mounted at its thin end between said locking member and the outer side of said recess and adapted to re-

movably hold the inner end of said locking member in engagement with one of said notches.

4. In combination with a bolt having a plurality of longitudinal notches, one of the faces of said notches being straight and the other of the faces sloped, of a nut provided with a diagonally extending recess, the inner end of said recess extending radially to said bolt and adapted to lie flush with the straight faces of said notches, the lower side of said recess adapted to lie flush with the sloping faces of said notches, said recess having its sides diverging from a point intermediate its ends, a transverse pin in said recess, a locking member pivotally mounted in said recess, said locking member having the inner end thereof arranged at a substantial obtuse angle of the body thereof, the extreme inner end of said member being beveled, and a tapering wedge member pivotally mounted at its thin end on said pin between said locking member and the outer side of said recess adapted to removably hold the beveled end of said locking member in engagement with the straight face and one of said notches.

In testimony whereof I affix my signature in presence of two witnesses.

WILLIAM KLOTZ.
